(57) **CLAIM**

The ornamental design for a stand upon protector for radiological cartridge, as shown.

DESCRIPTION

FIG. 1 is an isometric view of the stand upon protector for radiological cartridge of the present invention;

FIG. 2 is a front view of the stand upon protector for radiological cartridge of the present invention;

FIG. 3 is a rear view of the stand upon protector for radiological cartridge of the present invention;

FIG. 4 is a left side view of the stand upon protector for radiological cartridge of the present invention;

FIG. 5 is a right side view opposite FIG. 4 of the stand upon protector for radiological cartridge of the present invention;

FIG. 6 is a top view of the stand upon protector for radiological cartridge of the present invention; and,

FIG. 7 is a bottom view of the stand upon protector for radiological cartridge of the present invention.
